Des. 207,272
Patented Mar. 28, 1967

207,272

COMBINED LUMINAIRE AND POST

Harold E. Seals, Jr., Denver, Colo., assignor to Seals Enterprises Inc., Denver, Colo., a corporation of Colorado

Filed June 9, 1966, Ser. No. 2,617

Term of patent 14 years

(Cl. D48—31)

FIG. 2

FIG. 1

FIG. 1 is a side elevational view of a combined luminaire and post incorporating my design;

FIG. 2 is a top view thereof; and

FIG. 3 is a cross-sectional view of the post taken along section line 3—3, FIG. 1.

I claim:

The ornamental design for a combined luminaire and post, as shown and described.
